UNITED STATES PATENT OFFICE

2,340,670

METHOD OF ASSEMBLING ANODE
STRUCTURES

Ernest H. Lehman, Scotia, N. Y., assignor to General Electric Company, a corporation of New York

Application August 2, 1941, Serial No. 405,219

5 Claims. (Cl. 250—27.5)

My invention relates to means for and methods of simplifying and facilitating the manufacture of structures comprising cooperating threaded members which are to be provided respectively, before final assembly, with openings required to come into alignment when the members are screwed together to a desired degree of tightness.

The invention is directed especially to the provision of such means and methods in the manufacture of anode structures for mercury arc rectifiers or the like.

In Morton et al. Patent 2,286,755, dated June 16, 1942, and assigned to the same assignee as the present application, an anode locking system is disclosed and claimed wherein a locking member or washer is mounted between a flange portion of the anode stem and a surface of the anode tip. The locking member or washer includes extensions or tabs one or more of which are adapted to be bent, before the anode tip is screwed to the stem, into openings formed through the anode tip. The washer further includes one or more similar extensions or tabs adapted, after the tip is screwed to the stem, to be bent by means of a long punch or rod extended through other openings in the tip into corresponding openings formed in the flange portion of the anode stem and in alignment with those openings in the anode tip through which the punch is extended. The anode tip is thus locked in position on the stem and prevented from unscrewing therefrom during transportation and operation. The anode tip, however, may readily be disassembled from the stem by bending back the first-named washer extensions or tabs out of the anode-tip openings into which they extend, by means of the long punch or rod extended through these latter openings, thereby releasing the tip which may then be unscrewed from the stem.

In order to simplify and facilitate the construction and assembly on a practical manufacturing basis of the anode structure including the locking system requiring openings or pairs of openings in alignment in the finished structure as above described, it is highly desirable that these openings be formed accurately in such positions in the anode tip and stem respectively before assembly of these parts that when the tip is screwed tightly to its final position on the stem the corresponding openings will be in alignment.

It is therefore a particular object of my invention to provide an improved means for and method of constructing and assembling the above described anode structure.

In accordance with my present invention this object is accomplished by the provision of jig members respectively threaded correspondingly with the anode tip and the anode stem and having holes therethrough correspondingly respectively with and employed to indicate the positions of the openings in the anode tip and stem which are required to be in alignment when the anode structure is finally assembled.

10 The novel features which are considered to be characteristic of my invention are set forth with particularity in the appended claims. My invention itself, however, both as to its organization and method of operation together with further 15 objects and advantages thereof may best be understood by reference to the following description taken in connection with the accompanying drawing wherein Figs. 1 and 2 are respectively an elevational and cross-sectional view and a plan view 20 illustrating the form and construction of jig members utilized in carrying out the invention; Figs. 3 and 4 are respectively elevational and plan views of one of the jig members screwed to an anode tip; Figs. 5 and 6 are similar views of the 25 other jig member screwed to an anode stem; and Fig. 7 illustrates the final assembly of the anode structure.

Referring to Figs. 1 and 2, the numeral 1 designates a jig member which includes a threaded 30 stem portion 2 and a flange or other extension portion 3 having a flat surface 4 from which the stem portion 2 extends. The numeral 5 designates a second jig member, of any suitable form, for example cylindrical, in which is formed a 35 threaded hole 6 corresponding with the threaded stem portion 2 of jig member 1. The jig member 5 may preferably include a body portion 7 of relatively small diameter and a flange portion 8 at one end thereof having a flat surface 9.

40 The jig members 1 and 5 correspond respectively to the anode stem and anode tip of the anode structure, such as illustrated in Fig. 7, which is to be provided with openings required to be in alignment when the stem and tip are 45 screwed together, and the threaded portions 2 and 7 of the members 1 and 5 are characterized by the same screw diameter and screw form as are the corresponding threaded portions of this anode structure.

50 In forming the holes which are to be employed in jig members 1 and 5 for indicating the positions of the corresponding openings to be formed in the anode structure, the flange portion of one of the jig members, as member 1, may first be 55 bored through to form the desired holes, for ex-

ample the holes 10, 11, 12 and 13. The jig members 1 and 5 are then screwed tightly together with the surfaces 4 and 9 in close contact, reference marks 14 and 15 on the two members 1 and 5 being preferably provided which are in alignment when the members are in this position. Corresponding holes 16, 17, 18 and 19 in alignment respectively with the holes 10-13 of member 1 are then bored in the flange portion 8 of member 5 as by employing member 1 as a template.

Referring to Figs. 3 and 4, to form the hereinabove-mentioned required openings in an anode tip 20, the jig member 1 and the anode tip 20 are screwed tightly together with surface 4 of the jig member in close contact with an end surface 21 of the anode tip, a reference mark 22 being made on the anode tip 20 in alignment with the reference mark 14 of jig member 1 when the jig member and anode tip are in this position. Employing the flange portion 3 of jig member 1 as a template, the positions of openings 23, 24, 25 and 26 are indicated on the surface 21 of the anode tip and these openings are bored in the anode tip after removal of the jig member therefrom, or the openings 23-26 may be bored through the anode tip before removing the jig member. Metal inserts 27 and 28 at the ends of one or more of the openings, as 23 and 24, may be provided if the anode tip is of graphite.

Referring to Figs. 5 and 6, to form the required openings in an anode stem or stud 29 to be later assembled to the anode tip 20 of Figs. 3 and 4, the other jig member 5 and the anode stem 29 are screwed tightly together with surface 9 of the jig member in close contact with a flat surface 30 of a flange or other extension portion 31 of the stem, a reference mark 32 being made on the flange 31 in alignment with the reference mark 15 of jig member 5 when the latter jig member and the anode stem are in this position. Employing the jig member 5 as a template, the positions of openings 33, 34, 35, and 36 are indicated on the surface 30 of the flange portion 31 of stem 29 and these openings are then bored in the anode stem, either before or after the removal of the jig member 5 therefrom.

Referring to Fig. 7, after removal of the jig members 1 and 5 respectively from the anode tip 20 and the anode stem 29, and after the forming of the openings 23-26 in the tip and of the openings 33-36 in the stem, a locking member 37 having the form of a washer as described in the above-mentioned application Serial No. 396,584 is placed on the end surface 21 of anode tip 20, and locking extensions, as 38, with which the washer is provided, are bent into the holes 23 and 24 having the inserts 27 and 28. The anode stem 29 is then screwed into the anode tip 20 to bring the surface 30 of the stem and the surface 21 of the tip into contact, a recess 39 which is formed in the anode stem providing space for the washer.

It will be noted that any two corresponding holes, as 10 and 16 for example, in jig members 1 and 5 have been so located, as described in connection with Figs. 1 and 2, as to be in alignment when these jig members were screwed tightly together with reference marks 14 and 15 in alignment. It will further be noted that opening 23 of anode tip 20 was so located as to be in alignment with hole 10 of jig member 1 when the latter jig member and the anode tip were screwed tightly together with reference marks 14 and 22 in alignment, and that opening 33 of anode stem

29 was so located as to be in alignment with hole 16 of jig member 5 when the latter jig member and the anode stem were screwed tightly together with reference marks 15 and 32 in alignment. Therefore, upon screwing the anode tip 20 and stem 29 together as shown in Fig. 7 until their respective surfaces 21 and 30 are in close contact, like that close contact which obtained between the jig surfaces and the anode surfaces when forming the openings 23 and 33, the latter openings 23 and 33 will come into alignment as shown in Fig. 7, with reference marks 22 and 32 correspondingly in alignment.

After the anode members 20 and 29 are thus assembled in position with corresponding openings, as 23 and 33, in proper alignment, the anode members are, as described in the above-mentioned Morton et al. Patent 2,286,755, finally locked together against loosening or unscrewing by bending another tab or tabs, as 40, of the washer 37 into a corresponding opening or openings, as 36, of the anode stem 29.

The invention has been described herein in connection with the assembling of the tip and stem members of an anode structure. It is to be understood, however, that the invention is not limited to such application and that in general while the invention has been described in a particular embodiment for purposes of illustration, it is susceptible of various changes and modifications and that by the appended claims I intend to cover any such modifications as fall within the true spirit and scope of my invention.

What I claim as new and desire to secure by Letters Patent of the United States is:

1. Means for determining before the assembly of one threaded member to a second threaded member the respective positions of openings to be formed in said members and to be in alignment when said members are screwed together, said means comprising two jig members threaded respectively correspondingly with said first-named two members, said jig members having holes formed therethrough correspondingly to said openings, said holes being in alignment when said jig members are screwed together, said jig members being adapted to be screwed respectively to said first-named two members to indicate the positions of said openings therein.

2. Means for determining before the assembly of an anode tip to an anode stem the position of an opening to be formed in said tip and an opening to be formed in said stem, said openings to be in alignment when said tip and stem are screwed together, said means comprising two jig members threaded respectively correspondingly with said tip and stem, said jig members having holes formed therethrough correspondingly respectively to said openings, said holes being in alignment when said jig members are screwed together, one of said jig members being adapted to be screwed to said tip to indicate the position of said first-named opening therein through one of said holes, the other of said jig members being adapted to be screwed to said stem to indicate the position of said second-named opening therein through the other of said holes.

3. Means for determining in an anode tip and an extension portion of an anode stem the positions of openings adapted to be in alignment after said tip is screwed to said stem, said means comprising two jig members threaded respectively correspondingly with said tip and said stem, said jig members having holes formed there-

through and in alignment when said jig members are screwed together, said jig members being adapted to be screwed respectively to said tip and said stem to indicate through said holes the positions of said openings in said tip extension portion and said stem.

4. The method of assembling a structure having two threaded members adapted to have pairs of openings formed therein to be in alignment when said members are screwed tightly together, which comprises, providing jig members respectively threaded correspondingly with said threaded members, forming a pair of holes through each of said jig members corresponding respectively to said pairs of openings and in alignment when said jig members are screwed tightly together, screwing one of said threaded members tightly to the corresponding jig member, forming a pair of said openings in said one threaded member in accordance with the position of said holes in said last-named jig member, screwing the other threaded member tightly to the other jig member, forming a pair of said openings in said other threaded member in accordance with

the position of said holes in said other jig member, and screwing said threaded members tightly together.

5. The method of assembling an anode structure having a threaded anode tip and a threaded anode stem and adapted to have pairs of openings formed in said tip and stem to be in alignment when said tip and stem are screwed tightly together, which comprises, providing jig members respectively threaded correspondingly with said tip and stem, forming a pair of holes through each of said jig members corresponding respectively to said pairs of openings and in alignment when said jig members are screwed tightly together, screwing said tip tightly to the corresponding jig member, forming a pair of said openings in said tip in accordance with the position of said holes in said last-named jig member, screwing said stem tightly to the other jig member, forming a pair of said openings in said stem in accordance with the position of said holes in said other jig member, and screwing said tip and stem tightly together.

ERNEST H. LEHMAN.
